TUNING MECHANISM

Bertram A. Schwarz and Ludwig Fichter, Kokomo, Ind., assignors to General Motors Corporation, Detroit, Mich., a corporation of Delaware

Application February 15, 1940, Serial No. 319,044

5 Claims. (Cl. 74—10)

This invention relates to indexing mechanism and more specifically to indexing mechanism utilized with tuning means for automatically tuning a radio receiver to certain predetermined stations. Since most receivers are utilized mainly to receive transmitted signals from a relatively small number of stations which are usually those within the vicinity in which the receiver is located, it has become very popular to provide on each radio receiver a series of means whereby the tuning mechanism may be set to receive signals from any one of a plurality of stations by merely moving the button a short distance. The motion may be obtained either by pushing the member longitudinally or rotating it to a certain degree. Some of the earlier mechanisms applied to obtain this result were very cumbersome and included a great deal of mechanism.

It is the object of our invention to provide a simple, accurate and easily operated mechanism for automatically tuning a receiver to a plurality of predetermined stations.

It is a further object of our invention to provide such a tuning mechanism which may be easily manufactured, readily assembled, and operated over long periods of time without the necessity of adjustment.

With these and other objects in view, the embodiments of our invention will be better understood by reference to the following specification and claims and the illustrations of the accompanying drawings, in which:

Figure 1 is a front elevation of a set embodying our invention;

Figure 2 is a transverse sectional view taken on line 2—2 of Figure 3;

Figure 3 is a top plan view of the tuning mechanism of our invention;

Figure 4 is an enlarged detail view showing a portion of the apparatus for operating the indicator;

Figure 5 is a transverse sectional view taken on line 5—5 of Figure 3;

Figure 6 is a top plan view of the cover plate carrying the indicating mechanism which is applied over the tuning mechanism;

Figure 7 is an elevational view of the mechanism alone, taken on line 7—7 of Figure 6 and showing the supporting plate in section;

Figure 8 is an enlarged detail view of the connections between the tuning mechanism and rotatable member;

Figure 9 is an enlarged detail view showing the cooperation between the movable force applying

means and the movable shaft, taken on line 9—9 of Figure 10;

Figure 10 is an enlarged transverse sectional view showing one of the automatic tuning devices; and

Figure 11 is a detail view of one of the adjustable means which may be moved to change the automatic setting.

Referring now more specifically to the drawings, the front panel 2 of a set is shown in Figure 1. This panel is provided of course with an opening such as 4 through which a dial 6 is visible and over said dial an indicating needle 8 may be moved to provide information as to the station to which the radio receiver is tuned. Also extending through the front panel 2 are two comparatively large knobs 10 and 12, 10 being the manual tuning knob and 12 the switch and automatic volume control which is conventional as in any of the present sets. Between these two knobs 10 and 12 there are provided a series of smaller buttons 14 which in the present instance are five in number but may be of any number, dependent upon how many stations the manufacturer and/or user decides will be the convenient number. These buttons are the automatic tuning buttons and above each is provided a small opening 16 in which may be secured indicia showing by call letters which station that particular button is set for.

The tuning of a radio receiver may be accomplished by varying either the capacity in the resonant circuits therein or the inductance so that varying values of either one will provide a resonance of the circuit over a desired band. In the particular instance shown, we have illustrated the tuning of a set by varying the inductance, but the present mechanism may as satisfactorily be connected to variable capacities without deviating from our invention in any way. Since the particular tuning mechanism per se forms no part of the present invention, it is shown in dotted lines as is the outside casing and in Figure 2 we find an induction coil 18 which is supported in the rear of the outer casing and within the center of which there is adapted to be moved a small core 20. Since there are several tunable circuits in a receiver in the various stages, it is necessary to provide a plurality of these for tuning the whole receiver and there are shown in dotted lines in Figure 3 three of these variable inductances.

Within the forward portion of the casing there is provided a supporting box frame indicated generally at 22, having the forward and rear portions bent upwardly to provide vertical front and

rear walls 24 and 26. Within the forward wall there are provided a series of openings 28 through which the shafts of a series of rods 30 are carried for longitudinal movement. In alignment with these openings and in the rear wall there are provided a like series of openings 32 which support and trunnion the opposite ends of the rods 30. Applied to the forward end of the rod and rigidly secured thereon by gluing or other suitable means are the buttons 14 which extend through the forward face of the casing. Press-fitted upon each rod 30 and directly inside the upper vertical wall 24 is a small washer 34 which acts as a stop to prevent the rod from being ejected forwardly inasmuch as it is spring-biased toward that position by a helical spring 36 which surrounds the inner end of the rod between the inner face of the rear wall 26 and a second washer 38 thereon.

Between the two washers 34 and 38 the rod 30 is threaded as at 40 and has mounted thereon an angled bracket 42, as best shown in Figure 11, said bracket being provided with a horizontal portion and two vertical portions 44 and 46 having therein threaded openings 48, the vertical portion 44 having an extending tip 50 which projects downwardly into a longitudinal slot 52 in the base of the member 22. This prevents the bracket from rotating with the rod 30 and provides a screw feed for it along the axis. There is also provided on the forward face of the portion 44 a bulbous projection 54 whose purpose will be later explained. A small spring 56 which is slightly bowed is adapted to be inserted through the opening 45, between the upper portion of the member 42 and the threads of the rod to cause tension between the two so that there will be some force necessary to thread the member along the rod and the same will remain in a given set position. The tip of the rod which projects through the opening 32 in the vertical rear face 26 terminates in a small knob 58 which has a radial face adjacent the end of the rod.

There are also provided across the ends of the box frame 22 two end plates 60 and 62 and trunnioned therein is a flat plate 64 which is pivoted about one edge thereof. There is also provided a pair of springs 66, one end of each being connected adjacent the free end of this plate 64, the other end being connected to the frame so that the spring bias will force the plate upward to contact the knobs 58 on each of the longitudinal movable rods 30. The travel of these rods 30 is so designed that when they are in their innermost position the knob 58 will just pass over the inner edge of the spring-biased plate 64 as shown in the dotted line position in Figure 2, whereby the plate will act as a spring lock and prevent the rod 30 from returning to its original outward position normally caused by the spring 36. The upper surface of this plate 64 is angular, as best shown in a section of Figure 2, and the outer surface of the knob 58 is tapered to substantially correspond to the slant of this surface so that as one rod is forced inwardly the plate is forced down to first release any other knob which may be locked in, before it itself passes the edge of the plate and is locked therein whereby only one rod at a time is locked in its innerward indexing position. There is also provided a resilient washer 68 around the end of the rod projecting through the rear frame member 26 so that as the spring 36 forces the rod 30 outwardly the head of the member 58 will rest against this resilient washer and prevent noise in operation.

All of the rods 30 are exactly identical and the position of the adjustable member 42 along the threaded portion of each of the rods determines the indexing position of the tuning mechanism such as 18. The two end plates 60 and 62 of the box frame trunnion the ends of a transverse shaft 70 which extends the full width of the tuner and carries thereon at opposite ends two links 72, the links being connected to said shaft 70 adjacent one end and having rigidly secured thereto at an intermediate point a second parallel longitudinal shaft 74 which is adapted to cooperate with any of the adjustable members 42 for indexing purposes. Connected to the upper end of the links 72 is a third parallel shaft 76 to which are connected, through mechanism to be described, the tuning elements 20.

Adjacent the ends of the shaft 70 as shown in the lower portion of Figure 3 is a spring member 18, the body of which is wound around the shaft 70, one end extending out and being secured to the side frame member as shown in Figure 4 at 80, the other end extending up and being hooked over a projecting end of the upper shaft 76 as shown at 82. This spring-biasing means biases the assembly in a counterclockwise direction, as shown in Figure 2, which, it will be seen, is the position in which the tuning cores 20 will be substantially withdrawn from the central portion of the inductances 18.

The bulbous portion 54 of each adjustable bracket 42 is adapted to contact the forward surface of the shaft 74, as best shown in Figure 9, if the longitudinal rod is forced inward. This will cause the lever arms 72 to be rotated about their pivot on shaft 70 and therefore to carry with them the upper shaft 76 about the pivot 70. As the rod 30, which is being actuated, is allowed to return, the springs 18 will force the lever arms back to their outermost position.

Continuing now to describe more specifically the apparatus for connecting the upper shaft 76 to the tuning means 20, there is provided at spaced longitudinal positions on the shaft 76 a plurality of portions of smaller diameter, such as shown at 84, and secured in each one of these depressed portions is one end of a connecting link 86, shown in detail in Figure 8, and having a forward hooked portion 88 which extends over the body of the shaft 76. The opposite end of the connecting link 86 has a small pin 92 therethrough to which is secured a bushing support 94 having therein an internally threaded bushing 96 within which the threaded shaft 98, which is an integral part of the tuning core 20, is threaded. This allows the position of the core to be adjusted. Secured around the pin 92 and the shaft 76 are two ends of a small tension spring 100 which spring maintains the shaft 76 in the inward circular portion in the opening in the hooked end 88. Thus as the shaft 76 is rotated about the axis of the shaft 70, the mechanism just described connecting the shaft 76 with the member 20 causes the latter to move in and out of the induction coil 18. There are of course as many of these connecting mechanisms as there are tuning mechanisms which it is adapted to operate, and, as before mentioned, in the present instance there are three, as best shown in the dotted lines in Figure 3.

The manual tuning knob 10 is connected to a similar shaft 30' which is substantially identical to any one of the shafts formerly described, its detail being best shown by reference to Figure 5

wherein it will be seen that the shaft 30' carries an additional collar 102 adapted to act as a stop on the inward motion of the shaft 30' as well as having a washer 34' to act as a stop. The traveling threaded angle 42' is identical to the traveling angles 42 as is the spring bias 56' adapted to cause it to be biased against too loose movement along the threads. There is also a helical spring 36' to cause it to be ejected to an outermost position and a locking knob 58' which projects over the inner edge of the tilttable plate 54. The shaft 74, however, at this position has a flattened side as shown at 104 which flattened portion is adapted to contact the forward bulbous surface 54' of the angled bracket 42'. Otherwise the operation of the manual means is exactly the same as any of the others and may be best described by saying that the knob 10 is forced inwardly until the mechanism locks over the plate and then is rotated to cause the angled bracket to travel back and forth, rotating the lever arms 72 about the pivot 70 until the desired station is received. The actuation thereafter of any of the automatic knobs will cause the manual knob to be ejected.

Covering the box frame is a top plate 106 which is adapted to be secured thereto by suitable screws or bolts and carrying thereon any desired lighting means such as a bulb 108 and also indicating lever mechanism such as 110 which transmits the movement of the lever arms 72 to the indicating needle 8. This particular indicating mechanism provides straight line movement for the needle 8 by certain lever construction which however forms no part of the present invention. The operating mechanism for said indicating means comprises a lever 112 pivotally mounted at 114 to one of the levers 72, as shown in Figure 4 and at the lower portion of Figure 3, said lever 112 also being connected to the upper end of the member 72 by a pin and slot connection 116 so that its position may be adjusted. A pin 118 extends outwardly from the uppermost end of the lever 112 and has connected thereto a link 120, shown in dotted lines in Figure 4, to which is connected a suitable cord arrangement for transmitting the energy to the lever system above mentioned.

It will thus be evident that as the levers 72 are rotated about the shaft 70 as a pivot, the tuning cores 20 will be moved in and out of the associated inductance to cause necessary tuning of the radio receiver and at the same time the cord will transmit the necessary motion to the indicating needle 8 to show the position of the tuning mechanism, and, ordinarily, with none of the buttons 14 or 10 pushed inwardly, the levers 72 are spring-biased to an outward or counter-clockwise position.

In order to set up a plurality of stations on the automatic means associated with each of the buttons 14, it is only necessary to have the receiver in operation, then to depress one of the buttons 14 so that it locks the head of the member 58 over the edge of the plate, then rotate the rod 30 so that the angled bracket 42 may move along the axis of the same until a predetermined station has been reached. The next button is then depressed to the same extent which of course causes the release of the first rod in a manner formerly described and then this rod is rotated until another station has been brought into proper adjustment. This is repeated for all of the five or more buttons provided.

If at any time it is desired to manually tune the set the button 10 is depressed and the operation is exactly the same as in any one of the automatic adjustments. A further advantage of this construction is that the manual tuning knob 10 may be used as an automatic station selector inasmuch as it will always return the set to the last station set up thereon, its action being exactly identical with the remaining buttons 14.

10 It is also of course obvious that this same mechanism may be readily used to cause a variable condenser to rotate instead of actuating means for causing a core to be inserted within a coil to change the inductance as it would be very simple 15 to connect to the shaft 70 means to rotate a variable condenser and therefore the present illustrations are only illustrative of the broader conception of our invention.

We claim:

1. In indexing mechanism for tuning means, means rotatable about a pivot connected thereto, a plurality of reciprocable and rotatable rods at least a portion of each being threaded, threaded adjustable means mounted on each and adapted 25 to engage the rotatable means at a portion of its travel, means for locking the rods at the innermost position of travel at which position the adjustable means contacts the rotatable means whereby rotation of the rod will move the adjustable means and alter the position of the rotatable means and the associated tuning mechanism.

2. In indexing mechanism for tuning means, an assembly of parallel shafts pivoted to rotate 35 about the axis of one of them, means interconnecting the tuning means with a second of the shafts and a series of reciprocable means adapted to contact a third shaft to cause rotation of the assembly, said individual reciprocable means 40 alternatively actuating the third shaft.

3. In an indexing mechanism, a frame, a pivoted assembly mounted on the frame which it is desired to index, a plurality of rods mounted in the frame roughly at right angles to the assembly, 45 said rods being capable of reciprocation, spring means to bias them in one direction, a second spring means to bias the assembly in one direction, threaded means over a portion of each rod, threaded brackets mounted thereon and having a projection to engage the frame to prevent their rotation about the axis of the rods whereby as the rods are rotated the brackets may be adjusted axially thereof, said brackets being adapted to contact the assembly and move 55 it about its pivot against the spring-biasing pressure and locking means to maintain the reciprocating means at one extremity of its travel.

4. In an indexing device, a frame, means pivoted in the frame which it is desired to index to 60 different angular positions, a rod rotatably and reciprocably trunnioned in the frame, spring means biasing the rod in one direction, a threaded portion on the rod, a bracket threaded thereon and having a projecting portion engaging a slot in the frame to prevent its rotation about the axis of the rod but permit it to travel therewith for adjustment and spring-biasing means to maintain the pivoted means against the bracket whereby the position of the pivoted means may be varied either by rotation or reciprocation of the rod and means for locking 65 said rod at one extremity of travel.

5. In an indexing mechanism, a frame, a pivoted assembly carried thereby which it is desired 70 to index to different angular positions, a plu-

rality of rods mounted in the frame at substantially right angles to the assembly for both rotation and reciprocation, stops to limit the reciprocal travel of the rods, spring-biasing means for each rod to cause it to remain normally at one extremity of travel, a threaded portion on each rod, a threaded bracket mounted on each threaded portion having a projecting portion, said frame having a plurality of slots therein in which the projecting portions travel, the 10 brackets adapted to contact the assembly alternately, a pivoted plate carried by the rear of the frame below the rods and spring-biased up-

wardly, knobs mounted on the inner ends of the rods adapted to slide over the plate and lock the rod so forced, the action of the next operated rod releasing the one locked so that there can only be one rod locked in at one time, whereby when a rod is locked in the bracket thereon forces the assembly to a given position and the rod may be rotated to alter the position for slight adjustment and when the next rod having a different setting is depressed the first rod will be released.

BERTRAM A. SCHWARZ.
